DESIGN FOR A TABLE COVERING OR SIMILAR ARTICLE

Charles Emmey, New York, N. Y.

Application March 23, 1936, Serial No. 61,734

Term of patent 7 years

To all whom it may concern:

Be it known that I, Charles Emmey, a citizen of the United States, residing in the city and county of New York, State of New York, have invented a new, original, and ornamental Design for a Table Covering or Similar Article, of which the following is a specification, reference being had to the accompanying drawing forming part thereof.

Fig. 1 is an enlarged fragmentary plan view of a table covering or similar article, showing my design having decorations in the corners thereof.

Fig. 2 is a reduced view showing Fig. 1, with the decorations in relative proportion with the table covering.

Said table covering with the decorations thereon is of no appreciable thickness.

I claim:

The ornamental design for a table covering or similar article, substantially as shown and described.

CHARLES EMMEY.
